(57) **CLAIM**

The ornamental design for a threadable fuel cap, as shown and described.

DESCRIPTION

FIG. 1 is a front elevational view of a threadable fuel cap showing my new design;

FIG. 2 is a side elevational view thereof;

FIG. 3 is a top plan view thereof;

FIG. 4 is a bottom plan view thereof; and,

FIG. 5 is a perspective view thereof.

The broken line showing of environment is for illustrative purposes only and forms no part of the claimed design.
